UNITED STATES PATENT OFFICE

154,035

DESIGN FOR A PEN AND PENCIL CLIP

Floyd P. Griffith, Appalachia, Va.

Application July 15, 1948, Serial No. 147,577

Term of patent 3½ years

(Cl. D74—1)

To all whom it may concern:

Be it known, that I, Floyd P. Griffith, a citizen of the United States, residing at Appalachia, in the county of Wise, and State of Virginia, have invented a new, original, and ornamental Design for a Pen and Pencil Clip, of which the following is a specification, reference being had therein to the accompanying drawing, forming part thereof, in which

The essential features of my design for a pen and pencil clip reside in the configurations of the lever arm and clamp, in combination with the sun-ray type ornamentation at the top of the clamp.

I claim:

The ornamental design for a pen and pencil clip, as shown and described.

FLOYD P. GRIFFITH.
